UNITED STATES PATENT OFFICE.

JOHN E. WRIGHT, OF NEW YORK, N. Y., ASSIGNOR TO WRIGHT TELEGRAPHIC TYPE-WRITER COMPANY, OF NEW YORK, N. Y., A CORPORATION OF DELAWARE.

TRANSLATOR FOR PRINTING-TELEGRAPH SYSTEMS.

1,120,261.

Specification of Letters Patent.

Patented Dec. 8, 1914.

Application filed August 22, 1913. Serial No. 786,081.

To all whom it may concern:

Be it known that I, JOHN E. WRIGHT, a citizen of the United States, residing at New York, city, county, and State of New York, have invented certain new and useful Improvements in Translators for Printing-Telegraph Systems, of which the following is a full, clear, and exact description.

In a patent granted to me on March 17, 1914, No. 1,090,365, I have shown and described a printing telegraph receiving instrument, in which certain operations are performed by mechanisms which are non-interfering and hence capable of simultaneous action. For example, the type wheel, by one electrically controlled mechanism, may be rotated about its axis to bring a given vertical column of characters into register with the printing position, at the same time that, by another it is shifted in line with its axis to bring to printing position a given horizontal row of characters. This instrument, which is now referred to merely as typical of a class to which my present invention is applicable, contains a plurality of circuits local to itself by the completion of one or of several of which either successively or simultaneously, the various operations of bringing any given character on the type wheel into register, printing, spacing, paper feeding and the like, are effected.

The invention, subject of my present application, is an improvement in devices which may be defined as translators, and which comprise certain line controlled circuits operating through suitable electro-magnetic devices to select and operate that or those levers, or their equivalents, which, by the control of the proper receiver circuits, will effect the printing of a character or any other operation in such a receiver that corresponds to the number or character of the impulses constituting a signal sent over the line to the translator.

In another patent granted to me on March 17, 1914, No. 1,090,367, I have shown a translator designed for this purpose, in which the line controlled circuits, or those receiving impulses transmitted over the line, operate through the instrumentality of selecting devices to move or shift a different lever for each combination of impulses constituting a signal. But inasmuch as certain of such combinations correspond to charac-

ters on the type wheel of the receiver, the printing of which involves the simultaneous completion of two receiver circuits, some of the levers of the translator were required to complete two receiving circuits and others 60 but one, since with the construction employed, but one lever was operated by each combination of impulses.

The improvement which I have now devised provides, among other things, for the simultaneous operation of two levers in the translator whenever a character is to be printed that requires the type wheel to be both rotated and lifted from its normal position, or other operation performed 70 which necessitates the simultaneous completion of two receiver circuits. In this way the number of levers and size of the instrument as a whole are very much reduced, for whereas in the translator of my previous 75 application which was designed to operate with a receiver in which the type wheel was rotated four steps and lifted four steps from its normal position, twenty-four levers were required for all possible combinations 80 involved in its operation alone, only eight of such levers are needed to accomplish the same result in my improved device.

In addition to the features of construction by which this result is secured, I have 85 made other improvements in the details of construction of the apparatus, the nature of which will appear from the accompanying description.

The means by which I have accomplished 90 the above and the other results hereinafter referred to are illustrated in the accompanying drawings, in which—

Figure 1 is a front elevation of a translator constructed in accordance with my invention. Fig. 2 is a top plan and part sectional view of the same. Fig. 3 is a view of certain permutation rack bars employed in the device. Fig. 4 is a vertical section on line $x-x$ of Fig. 2. Fig. 5 is a similar section on line $y-y$ of the same figure. Fig. 6 is a section on line $z-z$. Fig. 7 is a front elevation of a modification of the invention. Fig. 8 is a plan view and part longitudinal section of the same. Fig. 9 is an end view 105 of the device Fig. 7, looking toward the left. Fig. 10 is a similar view looking toward the right. Fig. 11 is a side elevation of another modification. Fig. 12 is a top plan view of a portion of the same shown 110

as part of a diagram illustrating the means for operating the same by a transmission circuit; and Fig. 13 is a general diagram of circuit connections showing the relations of the translator to the line and to the receiving instrument.

Referring to Figs. 1 to 6 inclusive, the instrument illustrated thereby is, in the main, of the same construction as that made the subject of my prior Patent No. 1,090,367, above referred to. The operative portions of the device are mounted on a base plate 1, having two rigid side plates, 2 and 3, across which extend, in front, an angle bar 4 and in the rear a bar or plate 5. The bar 6, which also extends along the base plate in front, contains two groups of equi-distant slots or saw-cuts, in which the ends of two series of levers 7 and 8 are pivoted, the upper ends of said levers extending through slots in the angle bar 4, as shown in Fig. 4.

To each of the levers 7 and 8 a spiral spring 9, secured at its opposite end to a cross bar 10, is connected and operates to hold its lever in engagement with a movable cross bar 11, designed to normally limit the forward movement of the lever.

Extending across the device and sliding in suitable openings in the side plates 2 and 3, is a series or pile of six flat bars 12, which have the following special conformation. At its right hand end each bar has a projection 13 slotted to receive a steel wire spring 14 secured to the base plate 1, and which tends to hold the bar in proper alignment and force it toward the left. Each bar contains notches 15 at regular intervals and in position such that when one or more bars are shifted to the right one of a series of pivoted levers 16 will come forward and enter a vertical row of registering notches and lock the shifted bar or bars in such position. The left hand ends of the bars which project beyond the plate 3 are spread, as shown in Fig. 1, to engage with a corresponding series of levers 17, the nature and purpose of which will be described later. Finally, each bar 12 along its forward edge contains on one side of its center, a series of notches which occupy different positions in the respective bars, and on the other side of the center a single extended notch, so that in the normal position of the pile or group of bars none of the levers 7 or 8 may be shifted through its full operative arc, but when any one or more of the bars are shifted to the right a predetermined distance, certain notches in the three upper bars to the left of the center, or in the three lower bars to the right of the center, or in both bars, will coincide and permit the correspondingly placed lever 7 or 8 to be drawn forward to its full extent, forcing a spring contact 43 into engagement with a fixed terminal 42. In other words, the bars consti-

tute a series of permutation racks or bars for the two series of levers 7 and 8 respectively, and which, according to their relative adjustment, permit one of the levers 7 or one of the levers 8, or one of each series, to be shifted into operative position.

The bars 12 are moved or adjusted for this purpose by the co-operative action of six selecting magnets, three designated 18 and constituting one group, and three designated 19 constituting another; the shifting or releasing magnet 20 and the intermediate mechanism illustrated in Figs. 1, 2 and 5. The selecting magnets are arranged in any convenient manner so that the armature lever of each may engage one of a series of pins 21, engaging levers 17. The said levers 17 are normally held out of the path of the permutation bars by means of light springs 22, but when any of the selecting magnets is energized and its corresponding pin 21 forced forward, lever 17, which is engaged thereby, is turned to bring its end into the path of its corresponding permutation bar, and is retained in such position by one of a series of spring actuated latches 23, see Fig. 2, pivoted to a stationary portion of the frame.

The magnet 20, preferably in the form of a solenoid, is provided with armature cores 95 secured to a yoke 24 carried by the end of a reciprocating rod 25, mounted in suitable fixed bearings in the frame of the machine. The said rod is pivotally connected with a lever 26, the opposite end of which is pivoted to a block 27, carrying the lever 17. When magnet 20 is energized the lever 26 is rocked about its pivotal support and the block 27 forced to the right, carrying the levers 17 with it, but only such of these levers as have been tilted by the selecting magnets and are retained by the latches 23 will engage with the permutation bars.

In the rear of the instrument is a magnet or solenoid 28, the cores of which are secured to a yoke to which is pivotally connected a bell crank lever 32, mounted in a stud secured to the bar 5, and through such connection to the bar 11 by means of the connecting rod 33. The bar 11 is supported upon a rock shaft 34 by arms 35, and is held in its normal or forward position by an arm or latch 36 extending from a rock shaft 37. The bar 11 is forced in this position, if not already in it, by the operation of magnet 28, and released and permitted to swing back through a limited arc by any suitable device. For this purpose I employ bell-crank lever 38, Fig. 6, pivoted to plate 2. One arm of the said lever is connected with a sliding rod 39 having a connection, with provision for lost motion, with the armature of magnet 20, and by the reciprocation of said rod is oscillated, bringing its other end into engagement with and lifting an arm 40

rigid with the rock shaft 37. This movement of the lever 38 thus engages the latch or arm 36, frees bar 11 and permits the latter to swing back through an arc sufficient to permit the levers 7 and 8 to complete a full swing when not opposed by the permutation bars.

For an understanding of the operation of the apparatus and for such other details of construction as have not been specifically described, reference is made to the diagram Fig. 13.

I have already explained that the function of this device is to control the various circuits local to the receiver or printing mechanism, and it will be understood that the specific means by which the several elements of the instrument itself are operated to effect this result are in a large measure immaterial. As the device is constructed, however, it requires that current impulses be introduced to it through nine different paths, seven of which may be designated as line controlled circuits and which are as follows, viz., the six paths including the selecting magnets and another including a special magnet 41 which has to do with a certain operation of the printing mechanism and will be more fully hereinafter described, and two other paths, one of which is a receiver controlled circuit, including the magnet 28, and the other a circuit controlled by the sunflower and including the magnet 20. In practice, the current impulses, with the exception of those for energizing the clearing magnet 28 and the releasing magnet 20, are derived from the segments of a sunflower disk at the receiving station which distributes the line impulses to the proper translator circuits to bring about the operation of the receiver which corresponds to the particular group of impulses transmitted. To simplify the explanation of operation and at the same time describe more in detail certain features of construction which have been referred to in somewhat general terms, the operations accompanying the transmission of certain signals or groups of impulses will be followed.

Assume that the segments of the receiving sunflower, which instrument may be of any ordinary kind, but which I have specifically described in application filed by me on January 22nd, 1913, Serial No. 743,512, are connected respectively to terminals 44 to 51, and that a signal transmitted over the line consists of but two impulses, the first of which starts the sunflower in operation, the second being delivered to terminal 48. This latter impulse energizes one of the magnets 18, with the result that the lever 17 corresponding to that magnet is brought into the path of one of the permutation bars and there retained by a latch 23. By the movement of the sunflower the circuit including

magnet 20 is energized at the proper moment. The action of this magnet is followed by two operations; the lever 26 is forced to the left and the block 27 shifted to the right so that the locked lever 17 engages with one of the permutation bars and shifts it to the right where it is engaged by one of the latches 16 and locked. Another operation is the release of the latch 36 through the instrumentality of the connecting rod 39, the lever 38 and the arm 40, which results in the cross-bar 11 being retracted. This permits one of the levers 7 to come forward and enter the registering notches in the pile of bars 12 and close, through its appropriate contact 42, one of the circuits 52 to 64 of the receiver. For the purpose of illustration, it may be assumed that this is the receiver circuit which turns the type wheel one, two or more steps, each of which includes two vertical columns of characters, and brings into operation the printing and letter spacing devices. Each of such operations of the receiving instrument completes, as its final step, a circuit to the translator terminal 65, which includes the magnet 28, and by the operation of this magnet the bell-crank lever 32 is rocked, the cross bar 11 is forced forward carrying with it the levers 7 and 8 and the permutation bars restored to their normal position by means of the mechanism illustrated in Figs. 1, 4 and 6, this apparatus being the same as that employed in the translator of my pending application No. 743,511. This mechanism consists of a pivoted lever 66, one end of which is engaged by a projection extending from the armature core of the magnet 28 and operating to lift a rod 67 carrying stops, one of which engages the bar 68 connecting the ends of two bell crank levers 59 pivoted to the frame. The other ends are connected by a rod 70, the whole constituting a rocking frame, and when the magnet 28 is energized and the rod 67 raised, the bar 70 engages the latch levers 16 and releases whatever permutation bars may have been shifted to the right, whereupon said bars are shifted back to normal position by the springs 14.

In like manner assume that an impulse of current over the line is delivered to a terminal 44 of the translator, which includes one of the selecting magnets 19. Then by the same series of operations one of the levers 8 will be operated and that circuit of the receiver closed, which lifts the type wheel one or more steps and effects the other operations already described, as is more fully set forth in my application filed December 9th, 1912, Serial No. 735,682.

In like manner impulses of any one series or group constituting a signal may be delivered to two or all of the selecting magnets of either group, or to none of the mag-

80

85

90

95

100

105

nets of a group, or if the signal transmitted corresponds to a character on the type wheel which requires the latter to be both turned and lifted, or which effects some other operation in the receiver, one or more, or all or none of both groups of magnets 18 and 19 may be simultaneously energized to effect the desired operation.

In the system with which this apparatus is designed to be used, the turning movement imparted to the type wheel is measured by an angle including two character columns or multiples thereof, and to bring any intermediate column of characters into the printing position there is employed a shift magnet in the receiver which operates through any suitable mechanism to advance the type wheel in a rotary direction through one column space. The receiver circuit which, when energized, effects this operation is controlled by a special magnet 41, the construction and operation of which may be understood from Fig. 13. This magnet has two coils or windings 71 and 72, the former included in the circuit from the translator terminal 50 directly to the ground at terminal 73. When, therefore, a group of impulses is transmitted which requires the operation of the shift magnet in the receiver the last impulse of the signal is delivered to terminal 50 with the following result: Coil 71 is energized and the armature 74 of the magnet is attracted toward its core. This movement of the armature raises a spring 75 into contact with a fixed terminal and closes a circuit which includes terminal 76, coil or winding 72 of magnet 41, spring 75, contact spring 77 and a terminal 78 connected to a ground terminal 79. This circuit includes also a local source of current in the receiver, so that the magnet 41 remains energized until the circuit of the clearing magnet 28 is completed by the receiver, whereupon the magnet 80, which is included in that circuit, is energized, its armature 81 attracted and the circuit broken between spring 71 and stop 78.

The apparatus thus far described contains, as will now be seen, two features of novelty and improvement over those set forth in my prior Patent No. 1,090,367, these consisting, first, in the combination of what, in certain respects, may be regarded as two translators in one instrument with one actuating mechanism common to both, and secondly, in the employment of a shift magnet having two coöperating windings, one arranged to be instantaneously energized by a line impulse, and the other in a circuit closed by the magnetizing action of the first and maintaining itself closed until its circuit is interrupted by a clearing impulse acting through another magnet. As the present application is mainly based upon these features, description of the apparatus

with respect to other details and operations not necessary to their understanding is omitted for sake of brevity.

The plan of using two sets of selecting magnets and permutation bars, arranged for coöperative action in the manner described above, permits of arrangements of the elements of the device which secure great advantages resulting from simplicity of construction, economy in manufacture and effectiveness in operation. For example, in Figs. 7 to 10 the apparatus is shown in a much more simple and compact form, the essential feature of which is the use of two separate groups of permutation bars disposed on opposite sides of a short frame and each controlled by its appropriate group of selecting magnets, but shifted or operated by the same releasing magnet 20 and intermediate mechanism common to both. This change in arrangement necessitates modifications in certain details of construction, but none which are fundamental in character. For example, the element corresponding to the cross-bar 11 is an oscillating frame 82 carrying side bars 83 which form abutments for the levers 7 and 8 when frame 82 is in a horizontal position. The frame is normally locked in such position against the force of a spring 84 by means of a latch 85, but when the block 27 is shifted by releasing magnet 20, this latch is released by a rod 89 operatively connected with the armature of the releasing magnet in the same manner as in the forms of device illustrated above.

As all the other essential parts corresponding to those in the figures described in detail, are designated by like numerals in Figs. 7 to 10, the construction of the modification will be readily understood and such mechanical changes as are involved in that construction will be obvious.

In the forms of apparatus above set forth there are present between the selecting magnets and the permutation bars, intermediate mechanical devices by means of which the operation of the magnets is transmitted to the bars. These intermediate devices may, however, be dispensed with and the selecting magnets used to impart movement to the permutation bars directly. This improvement is illustrated in Figs. 11 and 12. In these figures, all other parts being, if so desired, the same as those described in the previously illustrated forms, the selecting mag- nets 18 and 19 are mounted on the base of the instrument and provided with vibrating armature levers 86 connected at their upper ends with slide bars 87 arranged in such positions that when any given magnet is energized its corresponding slide bar will be brought into engagement with one of the permutation bars 12 and force the latter over toward the right hand. In this way the desired permutations secured by its rel-

ative adjustment of the bars 12 may be secured. But in order that the bars, when displaced by their respective magnets, may be maintained in the positions to which they are shifted, each armature lever is provided with a contact 88 which, on the initial movement of the armature, closes a circuit through the magnet itself which maintains the latter energized until the operation for which the adjustment of the bars is made is completed. In illustration of this operation the diagram of Fig. 12 may be referred to. In this diagram 89 represents the sunflower, through the segments of which impulses of current are distributed to the several magnets 18 and 19. When any magnet is energized by an impulse of current from the line its circuit closer 88 coming in contact with a fixed stop 90 closes a circuit from the ground through battery 91, the cam contacts 93 of the circuit controller, which are normally closed during the rotation of that instrument, through the wire 92, the stop 90, the contact 88 through the coils of the magnet to ground.

A special feature of great value may be secured by this arrangement, namely, the capacity of the device for storing signals. It will be observed that while the line impulses that energize the magnets 18 and 19 are practically instantaneous, the magnets themselves will remain energized as long as the path 92 is completed. If, therefore, the circuit controllers 88 be composed of yielding springs and arranged to make contact immediately upon the movement of the armature levers, each magnet will remain energized whatever the position of the permutation bars 12. It may happen, therefore, that a signal is transmitted over the line before the operations attendant upon the preceding signal have been completed or the permutation bars restored to normal position. In such case the signal will be stored by the selecting magnets and transmitted to the receiving apparatus immediately upon the restoration of the bars 12 to their normal position.

With regard to that feature of improvement which involves the combination of two sets of permutation bars and selecting magnets, it should be understood that in the prior art the counterpart of such bars is found in corresponding elements of widely different form, such as plates and disks, and that my present invention is not limited to the specific bars shown.

What I claim is:

1. In a translator for printing telegraph systems, the combination with a series of receiver controlling circuits and a series of line controlled circuits, of two groups or sets of contacts, each adapted to complete a receiver controlling circuit and electromagnetically controlled selecting mechanism for each set of contacts, connected with the line

controlled circuits for bringing into operation one of the contacts of either or both sets, according to the signal transmitted over the line.

2. In a translator for printing telegraph systems, the combination with a series of receiver controlling circuits and a series of line controlled circuits, of two groups or sets of contacts, each of which controls a receiver circuit, means connected with the line controlled circuits for operating the contacts for both sets, and two sets of selecting magnets connected with the line controlled circuits for determining the contact of either or both sets so operated according to the signal transmitted over the line.

3. In a translator for printing telegraph systems, the combination with a series of receiver controlling circuits and a series of line controlled circuits, of two sets or groups of contact levers, each of which controls a receiver circuit, a set of shiftable permutation bars for each set of contact levers, normally restraining all of said levers from operation, and selecting magnets included in line controlled circuits for determining the particular bar or bars of one or both sets to be shifted to permit the operation of a contact lever in either or both sets corresponding to the signal transmitted over the line.

4. In a translator for printing telegraph systems, the combination with a series of receiver controlling circuits and two sets of oscillating contact levers for controlling the same, of a series of notched permutation bars for each set of contact levers and co-operating therewith, means for shifting one or more or all of the bars of either or both series to bring notches into alinement at different points, a series of line controlled circuits, electromagnets therein and means operated thereby for selecting the bar or bars of either or both series to be shifted.

5. In a translator for printing telegraph systems, the combination of two sets of contact levers, a series of notched permutation bars for each set, adapted to be shifted to bring the notches into alinement at different points and selecting magnets for determining the bar or bars of each series to be shifted, according to the character of the signal transmitted over the line.

6. In a translator for printing telegraph systems, the combination with a frame, of two sets of contact levers pivoted along opposite sides of the same, a series of notched permutation bars for each set of contact levers adapted to be shifted to bring the notches into alinement at different points, and selecting magnets for each series of bars for determining the bar or bars of either or both series to be shifted.

7. In a translator for printing telegraph systems, the combination with a series of receiver controlling circuits and a series of

Line controlled circuits, of contacts for completing the receiver controlling circuits, selecting means for determining the contact or contacts to be operated according to the nature of the signal transmitted over the line, a magnet adapted when energized to complete a receiver controlling circuit, the said magnet having two windings, one in a line controlled circuit and the other in a receiver controlled circuit completed by the operation of the magnet in response to an impulse received from the line.

8. In a translator for printing telegraph systems, the combination with a series of receiver controlling circuits and a series of line controlled circuits, of a series of permutation bars, contact levers for completing the receiver controlling circuits, selectively controlled by said bars, selecting magnets in the line controlled circuits and armatures therefor, adapted to engage with and shift the permutation bars according to the signals transmitted over the line.

9. In a translator for printing telegraph systems, the combination with a series of receiver controlling circuits and a series of line controlled circuits, of a series of permutation bars, contact levers for completing the receiver controlling circuits, selectively controlled by said bars, selecting magnets in line controlled circuits, armatures therefor adapted to engage with and shift the permutation bars according to the signals transmitted over the line, and circuit controllers adapted when operated by the selecting magnets in response to impulses received from the line to prolong the flow of current through said magnets until the completion of a signal.

In testimony whereof I affix my signature ⁴⁰ in the presence of two subscribing witnesses.

JOHN E. WRIGHT.
